UNITED STATES PATENT OFFICE.

FRANCESCO BARANELLO, OF BROOKLYN, NEW YORK.

DESIGN FOR A DOLL'S CRADLE.

53,670.

Specification for Design.

Patented Aug. 5, 1919.

Application filed April 5, 1919. Serial No. 287,841. Term of patent 3½ years.

To all whom it may concern:

Be it known that I, FRANCESCO BARANELLO, a subject of the King of Italy, and a resident of the city of New York, borough of Brooklyn, in the county of Kings and State of New York, have invented a new, original, and ornamental Design for a Doll's Cradle, of which the following is a specification, reference being had to the accompanying drawings, forming part thereof.

Figure 1 is a side elevation of a doll's cradle showing my new design; Fig. 2 is a plan view of the same; and Fig. 3 is an end view of the same.

I claim:

The ornamental design for a doll's cradle as shown.

FRANCESCO BARANELLO.
